UNITED STATES PATENT OFFICE.

GOODWIN B. SMITH, OF NEW YORK, N. Y., ASSIGNOR TO SMITH VENDING MACHINE CORP., OF NEW YORK, N. Y., A CORPORATION OF DELAWARE.

DESIGN FOR A CASING FOR A VENDING MACHINE.

Application filed August 31, 1925. Serial No. 14,667. Term of patent 14 years.

To all whom it may concern:

Be it known that I, GOODWIN B. SMITH, a citizen of the United States, residing at New York, in the county of New York and State of New York, have invented a new, original, and ornamental Design for Casing for a Vending Machine, of which the following is a specification, reference being had to the accompanying drawing, forming a part thereof.

The figure is a perspective view of a casing showing my new design.

I claim:

The ornamental design for a casing for a vending machine, as shown.

Signed at New York, in the county of N. Y. and State of New York, this 20 day of August, 1925.

GOODWIN B. SMITH.
